CLAIM

The ornamental design for an electronic training collar device, as shown and described.

DESCRIPTION

FIG. 1 is a perspective view of an electronic training collar device in accordance with the present design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The even-broken line in the figure drawing views represents unclaimed environment structure of the electronic training collar device only and forms no part of the claimed design.
